(57) **ABSTRACT**

In an array substrate and a display apparatus, a gate line receives a gate pulse during a present 1H period and a data line receives a pixel voltage having a polarity inverted at every frame. When a thin film transistor is turned on in response to the gate pulse during the present 1H period, a pixel electrode receives the pixel voltage through the thin film transistor during the present 1H period. A pre-charging part pre-charges the pixel electrode to a common voltage that is a reference voltage of the pixel voltage in response to a previous gate pulse during a previous 1H period.

ARRAY SUBSTRATE AND DISPLAY APPARATUS HAVING THE SAME

CROSS-REFERENCE TO RELATED APPLICATION

This application claims priority from and the benefit of Korean Patent Application No. 10-2006-0090247, filed on Sep. 18, 2006, which is hereby incorporated by reference for all purposes as if fully set forth herein.

BACKGROUND OF THE INVENTION

1. Field of the Invention

The present invention relates to an array substrate and a display apparatus including the array substrate. More particularly, the present invention relates to an array substrate that may improve response speed and a display apparatus including the array substrate.

2. Discussion of the Background

In general, a liquid crystal display includes a liquid crystal display panel including a lower substrate, an upper substrate facing the lower substrate, and a liquid crystal layer interposed between the lower substrate and the upper substrate to display an image.

The liquid crystal display panel may include a plurality of gate lines, a plurality of data lines, and a plurality of pixels connected to the gate lines and the data lines, all of which are formed on the liquid crystal display panel. The liquid crystal display panel includes a gate driving circuit directly formed thereon through a thin film process. The gate driving circuit sequentially outputs a gate signal to the gate lines.

Generally, a gate driving circuit includes a shift register in which plural stages are connected to each other one after another. That is, each stage applies a gate signal to a corresponding gate line and controls the drive of a next stage.

However, the number of the gate lines increases as the liquid crystal display panel becomes larger in size and higher in resolution. When the number of gate lines increases, an active period (one horizontal scanning period, 1H period) during which pixels connected to one row are operated is shortened. As a result, the charge rate of the liquid crystal may decrease, thereby decreasing the response speed of a display apparatus.

SUMMARY OF THE INVENTION

The present invention provides an array substrate that may improve response speed and display quality.

The present invention also provides a display apparatus including the above array substrate.

Additional features of the invention will be set forth in the description which follows, and in part will be apparent from the description, or may be learned by practice of the invention.

The present invention discloses an array substrate including a base substrate and a plurality of pixels arranged on the base substrate. Each pixel includes a gate line, a data line, a thin film transistor, a pixel electrode, and a pre-charging part. The gate line receives a gate pulse during a present 1H period (one horizontal scanning period), and the data line receives a pixel voltage having a polarity inverted at every frame. The data line is insulated from the gate line and crosses the gate line. The thin film transistor is connected to the gate line and the data line to output the pixel voltage in response to the gate pulse during the present 1H period. The pixel electrode is connected to the thin film transistor to receive the pixel volt-

2

age during the present 1H period. The pre-charging part pre-charges the pixel electrode to a common voltage that is a reference voltage of the pixel voltage in response to a previous gate pulse during a previous 1H period.

- 5 The present invention also discloses a display apparatus including an array substrate, an opposite substrate, a gate driving circuit, and a data driving circuit. The array substrate includes a base substrate and a plurality of pixels arranged on the base substrate, and an opposite substrate coupled to the 10 array substrate and facing the array substrate. The gate driving circuit applies a gate pulse to the pixels and the data driving circuit applies a pixel voltage having a polarity inverted at every frame to the pixels. Each pixel arranged on the array substrate includes a gate line, a data line, a thin film 15 transistor, a pixel electrode, and a pre-charging part. The gate line receives the gate pulse during a present 1H period (one horizontal scanning period), and the data line receives the pixel voltage. The data line is insulated from the gate line and crosses the gate line. The thin film transistor is connected to 20 the gate line and the data line to output the pixel voltage in response to the gate pulse during the present 1H period. The pixel electrode is connected to the thin film transistor to receive the pixel voltage during the present 1H period. The pre-charging part pre-charges the pixel electrode to a common 25 voltage that is a reference voltage of the pixel voltage in response to a previous gate pulse during a previous 1H period.

It is to be understood that both the foregoing general description and the following detailed description are exemplary and explanatory and are intended to provide further explanation of the invention as claimed.

BRIEF DESCRIPTION OF THE DRAWINGS

The accompanying drawings, which are included to provide a further understanding of the invention and are incorporated in and constitute a part of this specification, illustrate embodiments of the invention, and together with the description serve to explain the principles of the invention.

35 FIG. 1 is a plan view showing a liquid crystal display according to an exemplary embodiment of the present invention.

40 FIG. 2 is a circuit diagram showing one pixel having a horizontal pixel structure shown in FIG. 1.

45 FIG. 3 is a waveform diagram showing a variation of a pixel voltage according to a gate pulse in one pixel of FIG. 2.

FIG. 4 is a layout showing a pixel on an array substrate shown in FIG. 1.

50 FIG. 5 is a sectional view taken along lines I-I' and II-II' shown in FIG. 4.

FIG. 6 is a plan view showing a liquid crystal display according to another exemplary embodiment of the present invention.

55 FIG. 7 is a circuit diagram showing one pixel having a vertical pixel structure shown in FIG. 6.

FIG. 8 is a layout showing a pixel on an array substrate shown in FIG. 6.

60 FIG. 9 is a sectional view taken along lines III-III' and IV-IV' shown in FIG. 8.

FIG. 10 is a plan view showing a liquid crystal display according to another exemplary embodiment of the present invention.

65 FIG. 11 is a circuit diagram showing one pixel having a vertical pixel structure shown in FIG. 10.

FIG. 12 is a waveform diagram showing a variation of a pixel voltage according to a gate pulse in one pixel of FIG. 11.

DETAILED DESCRIPTION OF THE
ILLUSTRATED EMBODIMENTS

The invention is described more fully hereinafter with reference to the accompanying drawings, in which embodiments of the invention are shown. This invention may, however, be embodied in many different forms and should not be construed as limited to the embodiments set forth herein. Rather, these embodiments are provided so that this disclosure is thorough, and will fully convey the scope of the invention to those skilled in the art. In the drawings, the size and relative sizes of layers and regions may be exaggerated for clarity. Like reference numerals in the drawings denote like elements.

It will be understood that when an element or layer is referred to as being "on" or "connected to" another element or layer, it can be directly on or directly connected to the other element or layer, or intervening element or layers may be present. In contrast, when an element is referred to as being "directly on" or "directly connected to" another element or layer, there are no intervening elements or layers present.

FIG. 1 is a plan view showing a liquid crystal display according to an exemplary embodiment of the present invention.

Referring to FIG. 1, a liquid crystal display 500 includes a liquid crystal display panel 100 to display an image, a printed circuit board 400 arranged adjacent to the liquid crystal display panel 100, and a tape carrier package (TCP) 300 connecting the liquid crystal display panel 100 and the printed circuit board 400.

The liquid crystal display panel 100 includes an array substrate 110, a color filter substrate 120 facing the array substrate 110, and a liquid crystal layer (not shown) interposed between the array substrate 110 and the color filter substrate 120. The array substrate 110 is divided into a display area DA on which the image is displayed, a first peripheral area PA1, a second peripheral area PA2, and a third peripheral area PA3. The peripheral areas PA1, PA2, and PA3 are adjacent to the display area DA.

In the display area DA of the array substrate 110, a plurality of pixel areas is defined in a matrix configuration. Particularly, in the display area DA, the pixel areas are defined by a plurality of gate lines GL1~GLn (n is an even-number larger than 2) extending in a first direction D1 and a plurality of data lines DL1~DLm extending in a second direction D2 substantially perpendicular to the first direction D1. The color filter substrate 120 includes a plurality of color pixels (e.g. red, green, and blue pixels) corresponding to the pixel areas arranged thereon.

The first peripheral area PA1 is adjacent to the first ends of the gate lines GL1~GLn, and a first gate driving circuit 210 is arranged in the first peripheral area PA1 to sequentially apply a gate pulse to the gate lines GL1~GLn. The first gate driving circuit 210 includes a shift register in which plural stages are connected to each other one after another. Each stage includes an output terminal connected to a corresponding first end of a gate line GL1~GLn. Thus, each stage is sequentially turned on to sequentially apply the gate pulse to a corresponding gate line GL1~GLn.

The second peripheral area PA2 is adjacent to the second end of the gate lines GL1~GLn, and a second gate driving circuit 220 is arranged in the second peripheral area PA2 to sequentially apply the gate pulse to the gate lines GL1~GLn. The second gate driving circuit 220 includes a shift register having a plurality of stages connected to each other one after another. Each stage includes an output terminal connected to a corresponding second end of a gate line GL1~GLn. Thus,

each stage is sequentially turned on to sequentially apply the gate pulse to a corresponding gate line GL1~GLn.

Since the first and second ends of each gate line are connected to the first gate driving circuit 210 and the second driving circuit 220, respectively, the gate pulse is input through both ends of the gate lines, which may prevent delay of the gate pulse.

In the present exemplary embodiment, the first driving circuit 210 and the second driving circuit 220 are substantially simultaneously formed on the array substrate 110 through a thin film process. The thin film process may be the same as that applied to form the pixels. Accordingly, the first gate driving circuit 210 and the second driving circuit 220 are integrated on the array substrate 110, so that the driving chips on which the first gate driving circuit 210 and the second gate driving circuit 220 are mounted may be removed from the liquid crystal display 500. As a result, the productivity of the liquid crystal display 500 may be improved and the size of the liquid crystal display 500 may be decreased.

The third peripheral area PA3 is adjacent to one end of the data lines DL1~DLm, and a first end of the TCP 300 is attached to the third peripheral area PA3. A second end of the TCP 300 is attached to the printed circuit board 400. A data driving chip 310 that provides a pixel voltage to the data lines DL1~DLm is mounted on the TCP 300. Thus, the data driving chip 310 may provide the pixel voltage to the data lines DL1~DLm in response to various control signals from the printed circuit board 400.

First and second gate control signals output from the printed circuit board 400 are provided to the first gate driving circuit 210 and the second gate driving circuit 220 through the TCP 300, respectively. Thus, the first gate driving circuit 210 and the second gate driving circuit 220 provide the gate pulse to the gate lines GL1~GLn in response to the first gate control signal and the second gate control signal, respectively.

As shown in FIG. 1, the pixels arranged on the array substrate 110 have a horizontal pixel structure in which the length in the first direction D1 is longer than a length in the second direction D2. In the horizontal pixel structure, three consecutive pixels arranged along the second direction D2 corresponding to red R, green G, and blue B pixels are defined as one pixel in which one color is displayed. When compared to a vertical pixel structure, the number of data lines is decreased and the number of gate lines is increased in the horizontal pixel structure.

In a liquid crystal display 500 that employs the horizontal pixel structure, the number of data driving chips 310 outputting a data signal decreases due to the decreased number of data lines, which may improve the productivity of the liquid crystal display 500. On the other hand, although the number of gate lines increases, since the first gate driving circuit 210 and the second gate driving circuit 220 are integrated onto the array substrate 110 through a thin film process, the number of chips in the liquid crystal display 500 may not increase.

Hereinafter, the horizontal pixel structure will be described in detail with reference to FIG. 2, FIG. 3, FIG. 4, and FIG. 5.

FIG. 2 is a circuit diagram showing one pixel having the horizontal pixel structure shown in FIG. 1, and FIG. 3 is a waveform diagram showing a variation of the pixel voltage according to the gate pulse.

Referring to FIG. 2, one pixel includes a first pixel Pixj corresponding to a red pixel R, a second pixel P(i+1)xj corresponding to a green pixel G, and a third pixel P(i+2)xj corresponding to a blue pixel B. Each of the first, second, and third pixels Pixj, P(i+1)xj, and P(i+2)xj has a horizontal pixel structure.

The first pixel Pix_{ij} includes an ith gate line GL_i , a jth data line DL_j , a storage line SL , an ith thin film transistor T1_i , an ith pre-charging transistor T2_i , and an ith pixel electrode PE_i .

The ith thin film transistor T1_i is connected to the ith gate line GL_i and the jth data line DL_j . Particularly, the ith thin film transistor T1_i includes a gate electrode connected to the ith gate line GL_i , a source electrode connected to the jth data line DL_j , and a drain electrode connected to the ith pixel electrode PE_i .

The ith pre-charging transistor T2_i is connected between an $(i-1)^{\text{th}}$ gate line GL_{i-1} and the storage line SL . Particularly, the ith pre-charging transistor T2_i includes a gate electrode connected to the $(i-1)^{\text{th}}$ gate line GL_{i-1} , a source electrode connected to the storage line SL , and a drain electrode connected to the ith pixel electrode PE_i .

The second pixel $\text{P}(i+1)_{xj}$ includes an $(i+1)^{\text{th}}$ gate line GL_{i+1} , the jth data line DL_j , the storage line SL , an $(i+1)^{\text{th}}$ thin film transistor $\text{T1}_{(i+1)}$, an $(i+1)^{\text{th}}$ pre-charging transistor $\text{T2}_{(i+1)}$, and an $(i+1)^{\text{th}}$ pixel electrode PE_{i+1} .

The $(i+1)^{\text{th}}$ thin film transistor $\text{T1}_{(i+1)}$ is connected to the $(i+1)^{\text{th}}$ gate line GL_{i+1} , the jth data line DL_j and the $(i+1)^{\text{th}}$ pixel electrode PE_{i+1} . The $(i+1)^{\text{th}}$ pre-charging transistor $\text{T2}_{(i+1)}$ is connected to the ith gate line GL_i , the storage line SL , and the $(i+1)^{\text{th}}$ pixel electrode PE_{i+1} .

The third pixel $\text{P}(i+2)_{xj}$ includes an $(i+2)^{\text{th}}$ gate line GL_{i+2} , the jth data line DL_j , the storage line SL , an $(i+2)^{\text{th}}$ thin film transistor $\text{T1}_{(i+2)}$, an $(i+2)^{\text{th}}$ pre-charging transistor $\text{T2}_{(i+2)}$, and an $(i+2)^{\text{th}}$ pixel electrode PE_{i+2} .

The $(i+2)^{\text{th}}$ thin film transistor $\text{T1}_{(i+2)}$ is connected to the $(i+2)^{\text{th}}$ gate line GL_{i+2} , the jth data line DL_j , and the $(i+2)^{\text{th}}$ pixel electrode PE_{i+2} . The $(i+2)^{\text{th}}$ pre-charging transistor $\text{T2}_{(i+2)}$ is connected to the $(i+1)^{\text{th}}$ gate line GL_{i+1} , the storage line SL , and the $(i+2)^{\text{th}}$ pixel electrode PE_{i+2} .

As shown in FIG. 2 and FIG. 3, the first pixel Pix_{ij} pre-charges the ith pixel electrode PE_i to a common voltage V_{com} in response to an $(i-1)^{\text{th}}$ gate pulse $\text{Gi}-1$ applied to the $(i-1)^{\text{th}}$ gate line GL_{i-1} . Particularly, when the ith pre-charging transistor T2_i is turned on in response to the $(i-1)^{\text{th}}$ gate pulse $\text{Gi}-1$, the common voltage V_{com} applied to the storage line SL is applied to the ith pixel electrode PE_i through the ith precharging transistor T2_i . Thus, the ith pixel electrode PE_i is pre-charged to the common voltage V_{com} during a 1H period (an $(i-1)^{\text{th}}$ active period $\text{Ai}-1$) when the $(i-1)^{\text{th}}$ gate pulse $\text{Gi}-1$ is generated.

Then, the ith thin film transistor T1_i is turned on in response to the ith gate pulse Gi , so that an ith pixel voltage V_{pi} applied to the jth data line DL_j is applied to the ith pixel electrode PE_i during an ith active period Ai .

When a polarity of the ith pixel voltage V_{pi} applied to the ith pixel electrode PE_i is inverted at every frame, the common voltage V_{com} is applied to the ith pixel electrode PE_i as a reference voltage during the $(i-1)^{\text{th}}$ active period $\text{Ai}-1$. Thus, a time when the ith pixel voltage V_{pi} reaches to a target voltage may be shortened during the ith active period Ai , so that a response speed of liquid crystal may be improved.

The $(i+1)^{\text{th}}$ pixel electrode PE_{i+1} of the second pixel $\text{P}(i+1)_{xj}$ is precharged to the common voltage V_{com} in response to the ith gate pulse Gi during the ith active period Ai , and then receives an $(i+1)^{\text{th}}$ pixel voltage $\text{V}_{\text{pi}+1}$ in response to the $(i+1)^{\text{th}}$ gate pulse $\text{Gi}+1$ during an $(i+1)^{\text{th}}$ active period $\text{Ai}+1$.

The $(i+2)^{\text{th}}$ pixel electrode PE_{i+2} of the third pixel $\text{P}(i+2)_{xj}$ is pre-charged to the common voltage V_{com} in response to the $(i+1)^{\text{th}}$ gate pulse $\text{Gi}+1$ during the $(i+1)^{\text{th}}$ active period $\text{Ai}+1$, and then receives an $(i+2)^{\text{th}}$ pixel voltage $\text{V}_{\text{pi}+2}$ in response to an $(i+2)^{\text{th}}$ gate pulse $\text{Gi}+2$ during an $(i+2)^{\text{th}}$ active period $\text{Ai}+2$.

As described above, when the polarity of the pixel voltage applied to each pixel is inverted at every frame, present pixels are pre-charged to the common voltage that is a reference voltage of a polarity in response to a previous gate pulse, and then receive a target pixel voltage. Thus, the time required for the pixel voltage of each pixel to reach the target voltage may be shortened during the active period, so that the response speed of the liquid crystal may be improved.

FIG. 4 is a layout showing a pixel on the array substrate shown in FIG. 1, and

FIG. 5 is a sectional view taken along lines I-I' and II-II' shown in FIG. 4.

The array substrate 110 includes a base substrate 111 and the pixels arranged on the base substrate 111. Since the pixels have a same configuration, only one pixel will be described in detail with reference to FIG. 4 and FIG. 5.

Referring to FIG. 4 and FIG. 5, the $(i-1)^{\text{th}}$ gate line GL_{i-1} and the ith gate line GL_i are arranged on the base substrate 111 extending in the first direction D1. In the present embodiment, the ith gate line GL_i is defined as a present gate line and the $(i-1)^{\text{th}}$ gate line GL_{i-1} is defined as a previous gate line with reference to the $(ixj)^{\text{th}}$ pixel.

The gate electrode GE1 of the ith thin film transistor T1_i and the gate electrode GE2 of the ith pre-charging transistor T2_i are formed on the base substrate 111. Particularly, the gate electrode GE1 of the ith thin film transistor T1_i is branched from the ith gate line GL_i , and the gate electrode GE2 of the ith pre-charging transistor T2_i is branched from the $(-1)^{\text{th}}$ gate line GL_{i-1} .

The $(i-1)^{\text{th}}$ gate line GL_{i-1} , the ith gate line GL_i , the gate electrode GE1 of the ith thin film transistor T1_i , and the gate electrode GE2 of the ith pre-charging transistor T2_i , which are arranged on the base substrate 111, are covered by a gate insulating layer 112.

The jth data line DL_j extending in the second direction D2, a first storage line SL_1 , a second storage line SL_2 , and a third storage line SL_3 are arranged on the gate insulating layer 112. The first storage line SL_1 and the second storage line SL_2 extend in the first direction D1. Particularly, the first storage line SL_1 is arranged adjacent to the $(i-1)^{\text{th}}$ gate line GL_{i-1} and the second storage line SL_2 is arranged adjacent to the ith gate line GL_i . The third storage line SL_3 extends in the second direction D2 and connects the first storage line SL_1 and the second storage line SL_2 .

The source electrode SE1 and the drain electrode DE1 of the ith thin film transistor T1_i and the source electrode SE2 and the drain electrode DE2 of the ith pre-charging transistor T2_i are formed on the gate insulating layer 112. The source electrode SE1 of the ith thin film transistor T1_i is branched from the jth data line DL_j , and the drain electrode DE1 of the ith thin film transistor T1_i is spaced apart from the source electrode SE1 by a predetermined distance at an upper portion of the gate electrode GE1. The source electrode SE2 of the ith pre-charging transistor T2_i is branched from the first storage line SL_1 , and the drain electrode DE2 of the ith pre-charging transistor T2_i is spaced apart from the source electrode SE2 by a predetermined distance at an upper portion of the gate electrode GE2. Thus, the ith thin film transistor T1_i and the ith pre-charging transistor T2_i are completed on the base substrate 111.

The jth data line DL_j , the first, second, and third storage lines SL_1 , SL_2 , and SL_3 , the ith thin film transistor T1_i , and the ith pre-charging transistor T2_i , which are arranged on the gate insulating layer 112, are covered by a protective layer 113. The protective layer 113 is provided with a first contact hole C1 and a second contact hole C2 formed therethrough to

expose the drain electrode DE1 of the ith thin film transistor T1*i* and the drain electrode DE2 of the ith pre-charging transistor T2*i*, respectively.

The ith pixel electrode PE*i* is formed on the protective layer 113. The ith pixel electrode PE*i* includes a transparent conductive material. Also, the ith pixel electrode PE*i* is connected to the drain electrode DE1 of the ith thin film transistor T1*i* through the first contact hole C1 and is connected to the drain electrode DE2 of the ith pre-charging transistor T2*i* through the second contact hole C2.

According to the above, the ith pre-charging transistor T2*i* is connected between the previous gate line GL*i*-1 and the first storage line SL1 to pre-charge the ith pixel electrode PE*i* to the common voltage V_{com} in response to the previous gate pulse.

As an example of the present exemplary embodiment, in the pixel having the horizontal pixel structure, the first, second, and third storage lines SL1, SL2, and SL3 are formed from the same layer with the jth data line DL*j*. Thus, the source electrode SE2 of the ith pre-charging transistor T2*i* may be branched from one of the first, second, and third storage lines SL1, SL2, and SL3. Therefore, the process to form the ith pre-charging transistor T2*i* on the array substrate 110 may be simplified.

FIG. 6 is a plan view showing a liquid crystal display according to another exemplary embodiment of the present invention, and FIG. 7 is a circuit diagram showing one pixel having a vertical pixel structure shown in FIG. 6. In FIG. 6, the same reference numerals denote the same elements in FIG. 1, and thus, detailed descriptions of the same elements will be omitted.

Referring to FIG. 6, a liquid crystal display 503 includes a liquid crystal display panel 103 to display an image, a printed circuit board 400 arranged adjacent to the liquid crystal display panel 103, and a tape carrier package (TCP) 300 connecting the liquid crystal display panel 103 and the printed circuit board 400.

The liquid crystal display panel 103 includes an array substrate 110, a color filter substrate 120 facing the array substrate 110, and a liquid crystal layer (not shown) interposed between the array substrate 110 and the color filter substrate 120. The array substrate 110 is divided into a display area DA on which the image is displayed and a first peripheral area PA1 and a third peripheral area PA3 that are adjacent to the display area DA.

In the display area DA of the array substrate 110, a plurality of pixel areas is defined in a matrix configuration. The first peripheral area PA1 is adjacent to the first end of the gate lines GL1~GLn, and a gate driving circuit 210 is arranged in the first peripheral area PA1 to sequentially apply a gate pulse to the gate lines GL1~GLn. The gate driving circuit 210 includes a shift register having a plurality of stages connected to each other one after another. Each stage includes an output terminal connected to a corresponding first end of a gate line GL1~GLn. Thus, each stage is sequentially turned on to sequentially apply the gate pulse to the corresponding gate line of the gate lines GL1~GLn.

The third peripheral area PA3 is adjacent to one end of the data lines DL1~DLm, and a first end of the TCP 300 is attached to the third peripheral area PA3. A second end opposite to the first end of the TCP 300 is attached to the printed circuit board 400. A data driving chip 310 that provides a pixel voltage to the data lines DL1~DLm is mounted on the TCP 300.

As shown in FIG. 6, each pixel arranged on the array substrate 110 has a vertical pixel structure in which the length in the second direction D2 is longer than a length in the first

direction D1. In the vertical pixel structure, three consecutive pixels arranged along the first direction D1 corresponding to red R, green G, and blue B pixels are defined as one pixel on which one color information is displayed.

Thus, in a liquid crystal display 503 employing the vertical pixel structure, the number of data lines is increased and the number of gate lines is decreased when compared to the horizontal pixel structure shown in FIG. 1.

Referring to FIG. 7, one pixel includes a first pixel Pix*j* corresponding to the red pixel R, a second pixel Pix(j+1) corresponding to the green pixel G, and a third pixel Pix(j+2) corresponding to the blue pixel B. Each of the first, second, and third pixels has the vertical pixel structure.

The first pixel Pix*j* includes an ith gate line GL*i*, a jth data line DL*j*, a storage line SL, a jth thin film transistor T1*j*, a jth precharging transistor T2*j*, and a jth pixel electrode PE*j*.

The jth thin film transistor T1*j* is connected to the ith gate line GL*i* and the jth data line DL*j*. Particularly, the jth thin film transistor T1*j* includes a gate electrode connected to the ith gate line GL*i*, a source electrode connected to the jth data line DL*j*, and a drain electrode connected to the jth pixel electrode PE*j*.

The jth pre-charging transistor T2*j* is connected to the $(-1)^{th}$ gate line GL*i*-1 and the storage line SL. Particularly, the jth pre-charging transistor T2*j* includes a gate electrode connected to the $(-1)^{th}$ gate line GL*i*-1, a source electrode connected to the storage line SL, and a drain electrode connected to the jth pixel electrode PE*j*.

The second pixel Pix(j+1) includes the ith gate line GL*i*, a $(j+1)^{th}$ data line DL*j*+1, the storage line SL, a $(j+1)^{th}$ thin film transistor T1(j+1), a $(j+1)^{th}$ pre-charging transistor T2(j+1), and a $(j+1)^{th}$ pixel electrode PE*j*+1.

The $(j+1)^{th}$ thin film transistor T1(j+1) is connected to the ith gate line GL*i*, the $(j+1)^{th}$ data line DL*j*+1, and the $(j+1)^{th}$ pixel electrode PE*j*+1. The $(j+1)^{th}$ pre-charging transistor T2(j+1) is connected to the $(i-1)^{th}$ gate line GL*i*-1, the storage line SL, and the $(j+1)^{th}$ pixel electrode PE*j*+1.

The third pixel Pix(j+2) includes the ith gate line GL*i*, a $(j+2)^{th}$ data line DL*j*+2, the storage line SL, a $(j+2)^{th}$ thin film transistor T1(j+2), a $(j+2)^{th}$ pre-charging transistor T2(j+2), and a $(j+2)^{th}$ pixel electrode PE*j*+2.

The $(j+2)^{th}$ thin film transistor T1(j+2) is connected to the ith gate line GL*i*, the $(j+2)^{th}$ data line DL*j*+2, and the $(j+2)^{th}$ pixel electrode PE*j*+2. The $(j+2)^{th}$ pre-charging transistor T2(j+2) is connected to the $(i-1)^{th}$ gate line GL*i*-1, the storage line SL, and the $(j+2)^{th}$ pixel electrode PE*j*+2.

The first, second, and third pixels Pix*j*, Pix(j+1), and Pix(j+2) pre-charge the jth , the $(j+1)^{th}$, and the $(j+2)^{th}$ pixel electrodes PE*j*, PE*j*+1, and PE*j*+2 to a common voltage, respectively, in response to an $(i-1)^{th}$ gate pulse Gi-1 applied to the $(i-1)^{th}$ gate line GL*i*-1. Particularly, when the jth , the $(j+1)^{th}$, and the $(j+2)^{th}$ precharging transistors T2*j*, T2(j+1), and T2(j+2) are turned on by the $(i-1)^{th}$ gate pulse Gi-1, the common voltage applied to the storage line SL is applied to the jth , the $(j+1)^{th}$, and the $(j+2)^{th}$ pixel electrodes PE*j*, PE*j*+1, and PE*j*+2 through the jth , the $(j+1)^{th}$, and the $(j+2)^{th}$ precharging transistors T2*j*, T2(j+1), and T2(j+2), respectively. Thus, the jth , the $(j+1)^{th}$, and the $(j+2)^{th}$ pixel electrodes PE*j*, PE*j*+1, and PE*j*+2 are precharged to the common voltage during a 1H period (an $(i-1)^{th}$ active period) when the $(i-1)^{th}$ gate pulse Gi-1 is generated.

Then, the jth , the $(j+1)^{th}$, and the $(j+2)^{th}$ thin film transistors T1*j*, T1(j+1), and T1(j+2) are turned on during an ith active period in response to the ith gate pulse Gi in order to apply the jth , the $(j+1)^{th}$, and the $(j+2)^{th}$ pixel voltages applied through the jth , $(j+1)^{th}$, and $(j+2)^{th}$ data lines DL*j*, DL*j*+1, and DL*j*+2

to the jth , the $(j+1)^{th}$, and the $(j+2)^{th}$ pixel electrodes PE_j , PE_{j+1} , and PE_{j+2} , respectively.

As described above, a present pixel electrode is pre-charged to the common voltage during a previous active period, so that the time required for a pixel voltage to reach a target voltage may be shortened during a present active period. Especially, when a polarity of the pixel voltage applied to each pixel is inverted at every frame, the present pixels are pre-charged to the common voltage that is a reference voltage of a polarity, and then receives a target pixel voltage in response to a present gate pulse. Thus, the time required for the pixel voltage to reach the target voltage may be shortened during the active period, so that the response speed of the liquid crystal may be improved.

FIG. 8 is a layout showing a pixel on the array substrate shown in FIG. 6, and FIG. 9 is a sectional view taken along lines III-III' and IV-IV' shown in FIG. 8.

The array substrate 110 includes a base substrate 111 and a plurality of pixels arranged on the base substrate 111. Since each pixel has the same configuration, only one pixel (e.g. the $(ixj)^{th}$ pixel) will be described in detail with reference to FIG. 8 and FIG. 9.

Referring to FIG. 8 and FIG. 9, the $(i-1)^{th}$ gate line GL_{i-1} , the ith gate line GL_i , a first storage line SL_1 , a second storage line SL_2 , and a third storage line SL_3 are formed on the base substrate 111. The ith gate line GL_i is defined as a present gate line and the $(i-1)^{th}$ gate line is defined as a previous gate line with reference to the $(ixj)^{th}$ pixel. The $(i-1)^{th}$ gate line GL_{i-1} and the ith gate line GL_i extend in the first direction D_1 . The first storage line SL_1 and the second storage line SL_2 extend in the second direction D_2 parallel to each other and are arranged between the $(i-1)^{th}$ gate line GL_{i-1} and the ith gate line GL_i . The third storage line SL_3 extends in the first direction D_1 and connects the first storage line SL_1 and the second storage line SL_2 .

A gate electrode GE_1 of a jth thin film transistor T_{1j} and a gate electrode GE_2 of a jth pre-charging transistor T_{2j} are formed on the base substrate 111. Particularly, the gate electrode GE_1 of the jth thin film transistor T_{1j} is branched from the ith gate line GL_i and the gate electrode GE_2 of the jth pre-charging transistor T_{2j} is branched from the $(i-1)^{th}$ gate line GL_{i-1} .

The $(i-1)^{th}$ gate line GL_{i-1} , the ith gate line GL_i , the first, second, and third storage lines SL_1 , SL_2 , and SL_3 , the gate electrode GE_1 of the jth thin film transistor T_{1j} , and the gate electrode GE_2 of the jth pre-charging transistor T_{2j} , which are arranged on the base substrate 111, are covered by a gate insulating layer 112. The gate insulating layer 112 is provided with a third contact hole C_3 formed therethrough in order to expose one end of the first storage line SL_1 .

Then, the jth data line DL_j extending in the second direction D_2 is arranged on the gate insulating layer 112. Also, a source electrode SE_1 and a drain electrode DE_1 of the jth thin film transistor T_{1j} and a source electrode SE_2 and a drain electrode DE_2 of the jth pre-charging transistor T_{2j} are formed on the gate insulating layer 112. The source electrode SE_1 of the jth thin film transistor T_{1j} is branched from the jth data line DL_j , and the drain electrode DE_1 of the jth thin film transistor T_{1j} is spaced apart from the source electrode SE_1 by a predetermined distance at an upper portion of the gate electrode GE_1 .

The source electrode SE_2 of the jth pre-charging transistor T_{2j} is connected to the first storage line SL_1 , and the drain electrode DE_2 of the jth pre-charging transistor T_{2j} is spaced apart from the source electrode SE_2 by a predetermined distance at an upper portion of the gate electrode GE_2 . The source electrode SE_2 of the jth pre-charging transistor T_{2j} is

connected to the first storage line SL_1 through the third contact hole C_3 formed through the gate insulating layer 112. Thus, the jth thin film transistor T_{1j} and the jth pre-charging transistor T_{2j} are completed on the base substrate 111.

5 The jth data line DL_j , the jth thin film transistor T_{1j} , and the jth pre-charging transistor T_{2j} arranged on the gate insulating layer 112 are covered by a protective layer 113. The protective layer 113 is provided with a first contact hole C_1 and a second contact hole C_2 through which the drain electrode DE_1 of the $10 j^{th}$ thin film transistor T_{1j} and the drain electrode DE_2 of the jth pre-charging transistor T_{2j} are exposed, respectively.

The jth pixel electrode PE_j is formed on the protective layer 113, and the jth pixel electrode PE_j is connected to the drain electrode DE_1 of the jth thin film transistor T_{1j} through the 15 first contact hole C_1 and the drain electrode DE_2 of the jth pre-charging transistor T_{2j} through the second contact hole C_2 .

As described above, the jth pre-charging transistor T_{2j} is 20 connected between the previous gate line GL_{i-1} and the first storage line SL_1 to pre-charge the jth pixel electrode PE_j to the common voltage in response to the previous gate pulse.

In FIG. 8 and FIG. 9, a structure in which the first, second, and third storage lines SL_1 , SL_2 , and SL_3 are formed from the same layer as the ith gate line GL_i in a pixel having the vertical pixel structure has been described. However, in the pixel 25 having the vertical pixel structure, the first, second, and third storage lines SL_1 , SL_2 , and SL_3 may be formed from the same layer with the jth data line DL_j .

FIG. 10 is a plan view showing a liquid crystal display 30 according to another exemplary embodiment of the present invention. In FIG. 10, the same reference numerals denote the same elements in FIG. 6, and thus, detailed descriptions of the same elements will be omitted.

Referring to FIG. 10, a liquid crystal display 505 includes 35 an array substrate 110 that is divided into a display area DA on which the image is displayed, a first peripheral area PA1, a second peripheral area PA2, and a third peripheral area PA3. The peripheral areas PA1, PA2, and PA3 are adjacent to the display area DA.

40 In the display area DA of the array substrate 110, a plurality of pixel areas is defined in a matrix configuration. The first peripheral area PA1 is adjacent to the first end of the gate lines GL_1 ~ GL_n , and a first gate driving circuit 210 is arranged in the first peripheral area PA1 to sequentially apply a gate pulse 45 to the gate lines GL_1 ~ GL_n . The second peripheral area PA2 is adjacent to the second end of the gate lines GL_1 ~ GL_n , and a second gate driving circuit 220 is arranged in the second peripheral area PA2 to sequentially apply the gate pulse to the gate lines GL_1 ~ GL_n .

50 The third peripheral area PA3 is adjacent to one end of the data lines DL_1 ~ DL_m , and a TCP 300 is attached to the third peripheral area PA3. A data driving chip 310 that provides a pixel voltage to the data lines DL_1 ~ DL_m is mounted on the TCP 300.

55 As shown in FIG. 10, each pixel arranged on the array substrate 110 has a vertical pixel structure of which a length in the second direction D_2 is longer than a length in the first direction D_1 . In the vertical pixel structure, three consecutive pixels arranged along the first direction D_1 corresponding to red R, green G, and blue B pixels are defined as one pixel in which one color is displayed.

In FIG. 10, one data line is connected to two pixels that are 60 arranged on the left and right sides thereof. Thus, in the liquid crystal display 505 shown in FIG. 10, the number of data lines is decreased by half and the number of gate lines is increased by two times when compared to the liquid crystal display 503 shown in FIG. 6.

FIG. 11 is a circuit diagram showing one pixel having the vertical pixel structure shown in FIG. 10, and FIG. 12 is a waveform diagram showing a variation of a pixel voltage according to a gate pulse in one pixel shown in FIG. 11.

Referring to FIG. 11, one pixel includes a first pixel P_{Lixj} corresponding to a red pixel R, a second pixel P_{Rixj} corresponding to a green pixel G, and a third pixel $P_{Lix(j+1)}$ corresponding to a blue pixel B. Each of the first, second, and third pixels P_{Lixj} , P_{Rixj} , and $P_{Lix(j+1)}$ has a vertical pixel structure.

The first pixel P_{Lixj} includes an ith gate line GLi , a jth data line DLj , a storage line SL , a jth left thin film transistor $T1j$, a jth left pre-charging transistor $T2j$, and a jth left pixel electrode $PEj(L)$.

The jth left thin film transistor $T1j$ is connected to the ith gate line GLi and the jth data line DLj . Particularly, the jth left thin film transistor $T1j$ includes a gate electrode connected to the ith gate line GLi , a source electrode connected to the jth data line DLj and a drain electrode connected to the jth left pixel electrode $PEj(L)$.

The jth left pre-charging transistor $T2j$ is connected to the $(i-1)^{th}$ gate line $GLi-1$ and the storage line SL . Particularly, the jth left pre-charging transistor $T2j$ includes a gate electrode connected to the $(i-1)^{th}$ gate line $GLi-1$, a source electrode connected to the storage line SL , and a drain electrode connected to the jth left pixel electrode $PEj(L)$.

The second pixel P_{Rixj} includes an $(i+1)^{th}$ gate line $GLi+1$, the jth data line DLj , the storage line SL , a jth right thin film transistor $T3j$, a jth right pre-charging transistor $T4j$, and a jth right pixel electrode $PEj(R)$.

The jth right thin film transistor $T3j$ is connected to the $(i+1)^{th}$ gate line $GLi+1$, the jth data line DLj , and the jth right pixel electrode $PEj(R)$. The jth right pre-charging transistor $T4j$ is connected to the ith gate line GLi , the storage line SL , and the jth right pixel electrode $PEj(R)$.

The third pixel includes the ith gate line GLi , an $(j+1)^{th}$ data line $DLj+1$, the storage line SL , a $(j+1)^{th}$ left thin film transistor $T1(j+1)$, a $(j+1)^{th}$ left pre-charging transistor $T2(j+1)$, and a $(j+1)^{th}$ left pixel electrode $PEj+1(L)$.

The $(j+1)^{th}$ left thin film transistor $T1(j+1)$ is connected to the ith gate line GLi , the $(j+1)^{th}$ data line $DLj+1$, and the $(j+1)^{th}$ left pixel electrode $PEj+1(L)$. The $(j+1)^{th}$ left pre-charging transistor $T2(j+1)$ is connected to the $(i-1)^{th}$ gate line $GLi-1$, the storage line SL , and the $(j+1)^{th}$ left pixel electrode $PEj+1(L)$.

As shown in FIG. 11 and FIG. 12, the first and third pixels P_{Lixj} and $P_{Lix(j+1)}$ pre-charge the jth left pixel electrode $PEj(L)$ and the $(j+1)^{th}$ left pixel electrode $PEj+1(L)$ to the common voltage $Vcom$ in response to an $(-1)^{th}$ gate pulse $Gi-1$ applied to the $(-1)^{th}$ gate line $GLi-1$. Particularly, when the jth left pre-charging transistor $T2j$ and the $(j+1)^{th}$ left pre-charging transistor $T2(j+1)$ are turned on in response to the $(i-1)^{th}$ gate pulse $Gi-1$, the common voltage $Vcom$ applied to the storage line SL is applied to the jth left pixel electrode $PEj(L)$ and the $(j+1)^{th}$ left pixel electrode $PEj+1(L)$ through the jth left pre-charging transistor $T2j$ and the $(j+1)^{th}$ left pre-charging transistor $T2(j+1)$, respectively. Thus, the jth left pixel electrode $PEj(L)$ and the $(j+1)^{th}$ left pixel electrode $PEj+1(L)$ are pre-charged to the common voltage $Vcom$ during the 1H period (an $(i-1)^{th}$ active period $Ai-1$) when the $(-1)^{th}$ gate pulse $Gi-1$ is generated.

Then, the jth left thin film transistor $T1j$ and the $(j+1)^{th}$ left thin film transistor $T1(j+1)$ are turned on in response to an ith gate pulse Gi during an ith active period Ai to apply a jth left pixel voltage $Vpj(L)$ and a $(j+1)^{th}$ left pixel voltage $Vpj+1(L)$, which are applied through the jth data line DLj and the $(j+1)^{th}$

data line $DLj+1$, to the jth left pixel electrode $PEj(L)$ and the $(j+1)^{th}$ left pixel electrode $PEj+1(L)$, respectively.

Also, the jth right pre-charging transistor $T4j$ is turned on in response to the ith gate pulse Gi during the ith active period Ai , so that the common voltage $Vcom$ is pre-charged in the jth right pixel electrode $PEj(R)$. Then, when the jth right thin film transistor $T3j$ is turned on in response to the $(i+1)^{th}$ gate pulse $Gi+1$, a jth right pixel voltage $Vpj(R)$ is applied through the jth data line DLj to the jth right pixel electrode $PEj(R)$ during an $(i+1)^{th}$ active period $Ai+1$.

As a result, when a time during which pixels connected to one row are turned on is defined as a 1H period, even-numbered pixels among the pixels connected to one row are turned on in response to the ith gate pulse Gi generated during an earlier H/2 period, and odd-numbered pixels are turned on in response to the $(i-1)^{th}$ gate pulse $Gi-1$ during a later H/2 period. Also, the even-numbered pixels are pre-charged to the common voltage $Vcom$ in response to the $(i-1)^{th}$ gate pulse $Gi-1$, and the odd-numbered pixels are pre-charged to the common voltage $Vcom$ in response to the ith gate pulse Gi .

As described above, the time required for the pixel voltage to reach the target voltage may be shortened during the present active period since the present pixel electrode is pre-charged to the common voltage during the previous active period. Particularly, when the polarity of the pixel voltage applied to each pixel is inverted at every frame, present pixels are pre-charged to the common voltage, which is a reference voltage of polarity, and then receive the target pixel voltage. Thus, the time required for the pixel voltage to reach the target voltage may be shortened during the active period, thereby improving the response speed of the liquid crystal.

In FIG. 1, FIG. 2, FIG. 3, FIG. 4, FIG. 5, FIG. 6, FIG. 7, FIG. 8, FIG. 9, FIG. 10, FIG. 11, and FIG. 12, only structures in which the gate driving circuit is directly formed on an array substrate 110 have been described. However, the gate driving circuit may be prepared in the form of a chip to be mounted on the array substrate 110 in a chip-on-glass method or on the TCP.

Although not shown in figures, the method of the present invention in which the pixel electrode is pre-charged to the common voltage may be employed in liquid crystal displays with a wide viewing angle characteristics, for example, Patterned Vertical Alignment mode liquid crystal displays, Multi-domain Vertical Alignment mode liquid crystal displays, Super-Patterned Vertical Alignment (S-PVA) mode liquid crystal displays, etc.

Particularly, the S-PVA mode liquid crystal display includes a pixel having main and sub pixels to which different sub voltages are applied in order to form a domain having different gray-scales in the pixel. Since human eyes looking at the liquid crystal display only recognize an intermediate value between the two sub voltages, a deterioration of a lateral viewing angle due to a distorted gamma curve below an intermediate gray-scale may be prevented, thereby improving the lateral visibility of the liquid crystal display.

The above S-PVA mode liquid crystal display is classified into a coupling capacitor (CC) type and a two transistor (TT) type according to a driving method thereof. In the CC-type S-PVA mode liquid crystal display, a coupling capacitor is added between a main pixel electrode and a sub pixel electrode to drop a data voltage applied to the sub pixel electrode, so that a pixel voltage that is lower than the main pixel voltage is applied as a sub pixel voltage. Meanwhile, in the TT-type S-PVA mode liquid crystal display, a main pixel voltage and a sub pixel voltage having different voltage levels are applied to a main pixel electrode and a sub pixel electrode, respectively, using two transistors that are turned on for a predeter-

13

mined time interval. Thus, in case of the TT-type driving method, the time needed to charge the main and sub pixel voltages may be decreased by the H/2 period in comparison with the CC-type driving method.

Accordingly, in the S-PVA mode liquid crystal display employing the TT-type driving method, a charge rate of the liquid crystal in main and sub pixel areas may be improved since the main and sub pixel electrodes are pre-charged to the common voltage, thereby improving the response speed of the S-PVA liquid crystal display.

According to the above, the present pixel electrode is pre-charged to the common voltage that is the reference pixel voltage in response to the previous gate pulse during the previous 1H period, and the pixel voltage is applied to the present pixel in response to the present gate pulse during the present 1H period.

Thus, the time required for the pixel voltage of each pixel to reach the target voltage during the active period, in which present pixels connected to one row are operated, may be shortened, thereby improving the response speed of the liquid crystal.

Also, in conventional methods in which the present pixel is pre-charged to the previous pixel voltage, a ghost phenomenon where an image having a higher gray-scale than a desired gray-scale is displayed due to an overcharged present pixel may occur. However, according to exemplary embodiments of the present invention, the present pixel is pre-charged to the common voltage, which is used as the reference voltage of the pixel voltage. Thus, the ghost phenomenon may be prevented, thereby improving the display quality of the display apparatus.

It will be apparent to those skilled in the art that various modifications and variations can be made in the present invention without departing from the spirit or scope of the invention. Thus, it is intended that the present invention cover the modifications and variations of this invention provided they come within the scope of the appended claims and their equivalents.

What is claimed is:

1. An array substrate comprising:

a base substrate; and

a plurality of pixels arranged on the base substrate, each pixel comprising:

a gate line;

a storage line to receive a common voltage;

a data line to receive a pixel voltage, the data line being insulated from the gate line and crossing the gate line, wherein the pixel voltage has either a positive polarity or a negative polarity with respect to the common voltage, and the polarity of the pixel voltage is inverted every frame;

a thin film transistor connected to the gate line and the data line;

a pixel electrode connected to the thin film transistor; and

a pre-charging transistor comprising a first electrode connected to a previous gate line, a second electrode connected to the storage line, and a third electrode connected to the pixel electrode.

2. The array substrate of claim 1, wherein the storage line is formed from the same layer as the gate line.

3. The array substrate of claim 1, wherein the storage line is extended from and integrally formed with the second electrode of the pre-charging transistor.

4. The array substrate of claim 3, wherein the first electrode of the pre-charging transistor:

is branched from the previous gate line.

14

5. The array substrate of claim 1, wherein each pixel has a horizontal pixel structure in which a length of the pixel in a direction in which the gate line extends is longer than a length of the pixel in a direction in which the data line extends.

6. The array substrate of claim 5, wherein the storage line comprises:

a first storage line arranged adjacent to a previous gate line, the first storage line being substantially parallel to the previous gate line and overlapping the pixel electrode;

10 a second storage line arranged adjacent to the gate line, the second storage line being substantially parallel to the gate line and overlapping the pixel electrode; and a third storage line substantially parallel to the data line, the third storage line connecting the first storage line and the second storage line and overlapping the pixel electrode.

15 7. The array substrate of claim 1, wherein each pixel has a vertical pixel structure in which a length of the pixel in a direction in which the data line extends is longer than a length of the pixel in a direction in which the gate line extends.

20 8. The array substrate of claim 7, wherein the storage line comprises:

a first storage line and a second storage line spaced apart from each other, substantially parallel to the data line, and overlapping the pixel electrode; and

25 a third storage line substantially parallel to the gate line, the third storage line connecting the first storage line and the second storage line and overlapping the pixel electrode.

9. A display apparatus, comprising:

a display panel comprising an array substrate comprising a base substrate and a plurality of pixels arranged on the base substrate and an opposite substrate coupled to the array substrate and facing the array substrate;

30 a gate driving circuit connected to the display panel; and a data driving circuit connected to the display panel, each pixel comprising:

35 a gate line;
a storage line to receive a common voltage;
a data line to receive the pixel voltage, the data line being insulated from the gate line and crossing the gate line, wherein the pixel voltage has either a positive polarity or a negative polarity with respect to the common voltage, and the polarity of the pixel voltage is inverted every frame;

40 a thin film transistor connected to the gate line and the data line;

45 a pixel electrode connected to the thin film transistor; and

a pre-charging transistor comprising a first electrode connected to a previous gate line, a second electrode connected to the storage line, and a third electrode connected to the pixel electrode.

50 10. The display apparatus of claim 9, wherein the gate driving circuit is directly formed on the array substrate through a thin film process that forms the pixels on the array substrate.

55 11. The display apparatus of claim 10, wherein the gate driving circuit comprises:

60 a first gate driving circuit connected to a first end of the gate line; and

a second gate driving circuit connected to a second end of the gate line.

65 12. The display apparatus of claim 11, wherein the array substrate comprises a display area in which the pixels are arranged to display an image, a first peripheral area adjacent to the first end of the gate line, and a second peripheral area adjacent to the second end of the gate line, and

15

the first gate driving circuit and the second gate driving circuit are arranged in the first peripheral area and the second peripheral area, respectively.

13. The display apparatus of claim **11**, wherein each pixel has a horizontal pixel structure in which a length of the pixel in a direction in which the gate line extends is longer than a length of the pixel in a direction in which the data line extends.

14. The display apparatus of claim **13**, wherein the display panel further comprises red, green, and blue color pixels corresponding to three consecutive pixels arranged along the direction in which the data line extends, respectively, and

the three pixels serve as one unit pixel to display a color information.

15. The display apparatus of claim **11**, wherein each pixel has a vertical pixel structure in which a length of the pixel in a direction in which the data line extends is longer than a length of the pixel in a direction in which the gate line extends.

16. The display apparatus of claim **15**, wherein the display panel further comprises red, green, and blue color pixels corresponding to three consecutive pixels arranged along the

16

direction in which the gate line extends, respectively, and the three pixels serve as one unit pixel to display a color information.

17. The display apparatus of claim **16**, wherein the gate line receives a gate pulse from the gate driver during a present one horizontal scanning period (1H period),

odd-numbered pixels among the pixels arranged in one row are turned on during an earlier H/2 period within the present 1H period, and even-numbered pixels among the pixels arranged in the one row are turned on during a later H/2 period within the present 1H period.

18. The display apparatus of claim **17**, wherein the data line is to apply the pixel voltage to the odd-numbered pixels during the earlier H/2 period and to apply the pixel voltage to the even-numbered pixels during the later H/2 period.

19. The display apparatus of claim **17**, wherein the gate line comprises:

a first gate line to turn on the odd-numbered pixels during the earlier H/2 period; and
a second gate line to turn on the even-numbered pixels during the later H/2 period.
